UNITED STATES PATENT OFFICE

2,462,375

ARTICLE HOLDER

Bartholomew R. Flaherty, Shelton, Conn., assignor to Industrial Metal Products Laboratory, Ansonia, Conn., a partnership

Application October 6, 1945, Serial No. 620,779

3 Claims. (Cl. 248—309)

1

This invention relates to a holder for cups, cans and similar devices, such for example as cans for display in a grocery or other store, and has for an object to provide a simple and improved construction which will effectively hold the can, but in which the can may be easily mounted and from which it may be easily and quickly removed.

Another object is to provide such a construction which will be inconspicuous and may be easily mounted in the desired locations.

With the foregoing and other objects in view, I have devised the construction illustrated in the accompanying drawing forming a part of this specification. It is, however, to be understood the device is not limited to the specific details of construction and arrangement shown, but may embody various changes and modifications within the scope of the invention.

In the drawing:

Fig. 1 is a partial side elevation and partial section showing the device mounted on a support and with a can in position thereon;

Fig. 2 is a front elevation of the device;

Fig. 3 a side view;

Fig. 4 a transverse section on a somewhat enlarged scale, taken substantially on line 4—4 of Fig. 3, and

Fig. 5 is a similar section taken substantially on line 5—5 of Fig. 3.

The preferred construction shown comprises a housing or body member 10 which is preferably of a tubular construction and substantially rectangular in cross section. It may be drawn of seamless tubing, but is preferably formed from a flat piece of sheet metal with the side portions 11 bent forwardly from a rear or base wall 12, and the free edge portions of the sides 11 bent inwardly toward each other at 13, forming a front wall, with the edges of these portions abutting. The lower end portions of these walls 13 are extended forwardly and curved upwardly to form a hook or bend 14 to form a lower support for the article to be supported, such, for example, as the can 15 containing any suitable material to be displayed, such, for example as canned goods, paints and the like. The opposite ends of the rear wall 12 are extended beyond the sides 11 to form ears or lugs 16 for mounting the device on a suitable support, such as a wall or upright member 17, by suitable fastening means, such, for example, as screws 18, through openings 19 in these lugs.

The upper end of the container 15 is held by a hook or bend 20 on a variable slide 21 mounted within the housing or body 10 at the inner side

2

of the front wall 13. This slide may be a flat strip of metal of a width substantially the width of the interior of the body 10 and arranged with the hook or bend 20 extending forwardly over the top edge of the front wall 13. A coil spring 22 mounted within the housing 10 tends to move this slide downwardly and hold the hook or bend 20 in engagement with the article being held. A convenient and simple way of mounting and connecting the spring is to lance and bend forwardly a lug 23 from the rear wall 12 of the housing adjacent the lower end thereof, and to lance and bend rearwardly a similar lug 24 from the slide 21, and then to hook the opposite ends 25 of the spring over these lugs, the length of the spring being such as to be tensioned when in this position. This permits the slide 21 to be shifted upwardly various amounts to hold articles of different lengths, and the spring also tends to shift the slide downwardly and hold the hook or bend 20 tightly in engagement with the article. Thus, for example, in the case of the can 15 shown, which usually has a peripheral flange 26 at either end, the lower flange is seated in the hook or bend 14 while the hook or bend 20 is engaged over the upper flange, securely holding the device in position. The can may be easily and quickly inserted in position by placing its upper flange 26 under the upper hook or bend 20, then lifting it upwardly, carrying with it the slide 21, until its lower flange 26 can be seated in the lower hook or bend 14. It is as easily removed by simply reversing this operation, which merely comprises lifting the can upwardly to remove the lower flange from the lower hook 14 and then moving it forward and withdrawing the upper flange from the hook 20.

It will be understood this device is adapted for holding various articles, such as cups, cans and so forth, and that the shape and size of the hooks or bends 14 and 20 may be changed for holding different objects. Also, the adjustable slide 21 will accommodate articles of different lengths, and of course the lengths of the body 10 and the slide 21 can be made to correspond with the lengths of the articles it is planned to support in the device.

Having thus set forth the nature of my invention, what I claim is:

1. A holder of the character described comprising a flat strip of sheet metal including spaced side portions bent forwardly and then toward each other to form a tubular body adapted to be mounted in an upright position on a support, the lower edge of the front wall being provided

with an outwardly and upwardly curved bend to form a seat for the lower edge of an article, a slide mounted in the body provided at its upper end with an outwardly and downwardly curved bend to engage over the upper edge of the article seated in the lower bend, and a coiled spring in the body connected to the body and the slide and tending to shift the slide downwardly to retain its bend over the upper edge of the article.

2. A holder of the character described comprising a tubular body of substantially rectangular cross section, the rear wall of said body being extended to provide supporting means for fastening the holder to a support, a lower portion of the front wall being bent outwardly and upwardly to form a seat for the lower edge of an article to be supported, a slide mounted within the tubular body comprising a substantially flat strip guided between the side walls of the body at the inner side of the front wall and bent outwardly and downwardly at its upper end outside the front wall of the body to form a similar seat to engage over the upper edge of the article, and a coiled spring enclosed within the tubular body connected at its upper and lower ends to the slide and body respectively and tending to force the slide downwardly to clamp the article between the two seats.

3. A holder of the character described comprising a substantially rectangular tubular body

member provided at the upper and lower ends of its rear wall with lugs whereby it may be mounted on a support, the front wall of said body being provided at its lower end with an outwardly and upwardly curved portion forming a bend to form a seat for the lower edge of an article, a slide in the body provided at its upper end with an outwardly and downwardly curved portion forming a bend extending over the top edge of the front wall of the body to seat over the top edge of an article seated in the lower bend, said body and slide being provided with spaced laterally extending lugs, and a coiled spring enclosed in the body connected at its opposite ends to said lugs and tending to shift the slide downwardly to hold the upper bend against the edge of the article.
